UNITED STATES PATENT OFFICE.

JAMES M. HINCHEY, OF RUTLAND, VERMONT.

SCALE-BEAM PIVOT.

Application filed April 26, 1922. Serial No. 556,638.

This invention relates to scales, and has to do with the pivots employed upon the scale beam.

An object of the invention is to provide 5 a novel pivot construction which may be provided at materially less expense than the pivots ordinarily employed, and which will, at the same time, be securely held in position, thus insuring accuracy of the scale.

10 A further object of the invention is to afford a new and improved method for securing in position scale beam pivots, the method being of a character which will insure a perfect fit for the pivot bar with a 15 substantial saving in the time and labor employed in practicing the methods heretofore known and used.

In the accompanying drawings, and in the following detailed description there is 20 minutely described one practical embodiment of the method and of the pivot construction constituting the invention, although it will be understood that numerous modifications may be made in both the 25 method and in the pivot construction without departing from the invention, the scope of which is defined by the prior art and more definitely set forth in the claims.

In the drawings:—

30 Fig. 1 is a side elevational view of a scale beam showing the pivots in position,

Fig. 2 is a cross section showing the pivot in elevation,

Fig. 3 is a cross section showing the pivot 35 bar supporting plug in section, and

Figs. 4, 5, 6 and 7 are, respectively, illustrations disclosing the successive steps of the method for securing the pivots in the beam.

Referring to the drawings for a more detailed description, 40 indicates a beam of a well known type having therein a plurality of knife edge pivots 11 located, as shown in the drawings, in customary relation upon the beam. The beam, which, ordinarily, is 45 of brass or relatively hard metal, has, initially, formed therein for the insertion of a pivot an opening 12 (Fig. 4), ordinarily round, although other shapes of holes may be struck out. This hole is preferably produced by drilling and reaming so as to afford

a very accurate and finished opening in the beam. The next step in the method consists in forming a substantially V-shaped notch 13 at one point along the edge of the opening, which may be accomplished by broach-

ing out the opening, as shown in Fig. 5. A plug 14 having a keyway 15 therein, and which is substantially the same shape and size of the opening so as to accurately fit the latter, is then positioned in the opening with its keyway opposite and registering with the notch 13. The keyway may be of the same depth throughout the plug, as shown in Fig. 2 or may vary in depth longitudinally of the plug, as shown in Fig. 3, 65 and the plug is preferably formed of metal which is relatively soft as compared to the metal of the beam itself. The plug should accurately and tightly fit the opening, and prior to its insertion should 70 be carefully machined for this purpose.

After the insertion of the plug within the opening a pivot bar 16 having a knifed edge 17 is inserted in the keyway with its knifed edge fitting into the notch 13. It is desirable 75 that the knifed edge of the pivot bar tightly fit the broached portion constituting the notch, but should this fit not be as accurate as the fit of the plug in the opening the pivot will, nevertheless, be held firmly in 80 position. It will be understood, of course, that should the keyway in the plug be of uniform depth throughout the plug a pivot bar, such as is shown in Fig. 2, is employed, the bar in this figure being of the same 85 width or depth from end to end. However, when a plug such as is shown in Fig. 3 is used, the tapering pivot bar shown in this figure is employed and there is thus produced a wedging action which results in the 90 wedging of both the plug and the pivot bar in the opening. The pivot bar is of relatively hard metal as compared to the plug, and when placed in position in the manner above described and shown in the drawings 95 it constitutes a rigid, accurate and substantially immovable support for the bails or the like having bearings thereon.

It will be understood that the steps of the method above described may be carried 100 out in relatively different order and that such modifications may be made in the method and illustrated pivot construction as come within the scope of the invention.

I claim:

1. In a device of the class described, a beam having a substantially round bore therethrough, said bore having its edge cut away to form a notch, a substantially round plug fitting snugly in said bore and having 110

a keyway opposite said notch, and a pivot bar seated in said keyway, said bar projecting into the opening and into said notch.

2. A scale beam having an opening therein provided with a notched edge portion, a plug closely fitting said opening, said plug having a keyway therein, and a pivot bar in said keyway having a knife edge fitting into said notch, said keyway varying in depth 10 longitudinally of the plug and said pivot bar being longitudinally tapered whereby both the plug and bar are wedged in said opening.

3. In a device of the class described, a beam having an opening therein, the major portion of which is substantially round, a 15 round plug snugly fitting in said opening and having a keyway therein serving to receive a pivot bar, and a pivot bar in said

keyway extending into the opening and being wedged therein, the edge of said opening having a substantially V-shaped cut away portion and said pivot bar fitting into said portion.

4. In a device of the class described, a beam having a substantially round bore therethrough, said bore having its edge cut away to form a notch, a substantially round plug fitting snugly in said bore and having a keyway opposite said notch, a pivot bar seated in said keyway, said bar projecting into the opening and into said notch, and means for wedging said pivot bar in said groove.

In testimony whereof I have hereunto set my hand.

JAMES M. HINCHEY.
